APPARATUS AND METHOD FOR MEASURING
THE ACUITY OF HEARING

Aaron Roth, Brooklyn, N. Y.

Application March 17, 1932. Serial No. 599,454

17 Claims. (Cl. 181—0.5)

This invention relates to an apparatus for measuring the acuity of hearing, clinically referred to as an acousticometer, and particularly to the method of making comparative tests between the hearing of a patient or any other individual as a subject, and that of a person possessing normal hearing sense.

The method heretofore employed in effecting a test of this character generally consisted of vibrating by impact a series of sound producing media, such as tuning forks of predetermined pitches, successively placing each of said vibrating media in close proximity to the ear of the patient who indicates by a signal when he ceases to hear the sound, and then placing said vibrating media to the ear of the examiner or a person of normal hearing sensitivity, and holding it there until he ceases to hear the sound. The time elapsing between the points of lost audibility 20 of the patient and the examiner as so obtained indicates how much below normal is the hearing acuity of the patient. This interval of time will hereinafter be referred to as the acoustic differential,—indicating the time in seconds elapsing 25 between the instant the patient ceases to hear the sound and the instant the person with normal hearing ceases to hear the sound from the same instrument. The acoustic differential for each patient, for a series of different and predetermined pitches, is thus determined and can be 30 properly plotted on what I call an acumetric chart, which will hereinafter be more fully described.

This method of testing has proven to be unsatisfactory and inaccurate, particularly in view 35 of the fact that the findings are based upon repeated tests of a normal hearing sensitivity, and as this involves a repetitious use of the human element to obtain a standard, the standard so obtained is quite variable and the results consequently unreliable. Assuming that the examiner 40 is the person with normal hearing, every time the sound emitting instrument is applied to test the hearing of a patient, it must also similarly be applied to the ear of the examiner. If many of 45 such examinations are conducted, not only is this a physical and mental strain upon the examiner, but due to the inevitable nerve fatigue that will set in, his sensibilities in this direction 50 will be affected and rendered more or less valueless as a basis of comparison. This is particularly the case when examining persons very hard of hearing, often necessitating an unduly prolonged application of the instrument to the ear 55 of the examiner to determine his own point of

lost audibility, such determination being, as explained, an essential step in this method. Furthermore, such a method consumes considerable time, due to the fact that there is a virtual repetition of the test for both the patient and the examiner. It is to overcome these defects that I have conceived this invention, which aims to eliminate the human element as a standard basis of comparison, and to substitute therefor a mechanical method of obtaining with accuracy and precision the degrees of acuity of hearing for patients of various stages of deafness. And it is still a further object to reduce the time required to conduct a test of this nature and thereby enable the examiner to conduct a greater number of tests in a given time, without any great strain on him.

Other features, advantages, and objects will be more fully set forth in the description hereinafter given and will more clearly appear from the drawing herein.

Referring to the drawing:

Figure 1 is a front view of the apparatus constituting my invention; and Figure 2 is a side sectional view thereof along line 2—2 of Figure 80 1, showing three different positions of the pendulum.

Figure 3 is an enlarged fragmentary section of one of the tuning forks and the mounting therefor to permit vibratory freedom.

Figure 4 is a representation of the acumetric chart I employ to record the comparative findings of a tested ear and a normal one, as determined by the use of this apparatus.

Figure 5 is a perspective view of a single-pitch 90 unit, comprising a tuning fork and attached thereto my combination ear rest and fatigue shutter.

In the drawing, the pendulum 10 pivotally connected at 11 to the frame 12 has a rubber tipped 95 hammer 13 thereon. Although the particular structure herein disclosed illustrates a pendulum, a falling weight or a mechanical impact device of any other suitable structure may be substituted therefor. It is also preferable, though not absolutely essential, that the pendulum herein shown be made of resilient steel. Attached to the frame 12 is the pendulum release 14 which is adapted to frictionally hold the pendulum at a predetermined height; and upon a pressure applied to the 105 element 15 against the action of the spring 16, the pendulum is left free to swing downwardly under the action of gravity to strike the tuning forks thereunder, which will hereinafter be fully described.

110

The forks 17, 18, 19, 20, 21 and 22 are so mounted as to permit full vibratory freedom thereof, the lower extremities of the shanks of said forks being set into the recesses at the tops of the uprights 23, 24, 25, 26, 27 and 28. The collars 29 of rubber or other yieldable material, fit over the reduced lower portions of the shanks of the forks, each such collar frictionally holding together the assembly of fork and upright. These collars and 10 the pads 30 of similar material serve the purpose of absorbing, due to their compressibility, the vibrations of the tuning forks, thereby minimizing the transmission of these vibrations through the uprights to the base. Such an arrangement 15 permits of the maximum period of vibration of the forks, and produces results similar to that obtained when holding the fork in the hand. To further provide against restriction to vibratory movement, each upright has its lower end pivotally mounted at 31, and is provided with the intermediate support 32 containing the rollers 33 and 34 of yieldable material; or if preferred, instead of rollers padded elements may be employed. These engage the uprights, serving as auxiliary 25 means to keep them in their upright positions, yet being adapted to permit slight vibratory movements. It should be noted that the uprights are of such lengths as to render the upper ends of the tuning forks in substantial horizontal 30 alignment.

Although tuning forks are here employed, it is to be understood that any other suitable sound emitting device can be employed in the place thereof, provided it is adaptable to receive the impact of a falling weight or of a mechanically actuated hammer, and produce a sound thereby. Regardless of what medium is employed in the production of sound, it is generally advisable to 35 arrange a series of such instruments progressively in accordance with their pitches, it being highly desirable for test purposes that each successive instrument have a vibration period which is a multiple of that of the preceding instrument.

The bracket supports 35 are mounted on a movable carriage base 36 which is operatively connected through the carriage bolt 37 to the handle 38, so that a turning of the handle will successively bring each of the tuning forks mounted on the base into position to receive the impact of 40 the hammer 13. It is of course understood that in place of the geared arrangement herein shown, any other device for moving the base can be employed within the contemplation of my invention.

The ear rest 39, consisting of a circular ring-like member with a central aperture therein, is 45 attached to the stem 40 which is mounted upon the stationary frame work of this apparatus. Pivotaly mounted thereon at 41 is the fatigue shutter 42 having the lever arm 43 extending outwardly,—said shutter being positioned between the aperture in the ear rest and the tuning forks behind it. The said shutter may contain 50 a felt shield or other sound insulating material thereon, not shown in the drawing.

To conduct a test by using this apparatus, the patient places his ear at the ear rest 39, and the carriage is moved until the first tuning fork 17 is adjacent thereto and in a position to receive the impact of the hammer 13, which is set at the 60 same height that was used in the initial test of the person of normal hearing for creating a standard of comparison. The pendulum 10 is released by the operation of the member 14, and simultaneously with such release a stop watch is 70 set into operation. When the element 15 is de-

pressed, it is held in that position not only until the hammer strikes the tuning forks at position A, but for an instant thereafter as well, so that the hammer will rebound until frictionally held against further movement in position B by the release of said element 15. This arrangement prevents a series of impacts and rebounds, and permits only a single effective blow on the sound producing instrument by the operation of pendulum release 14.

The patient listens for the sound, and when he ceases to hear it, he indicates by an appropriate signal when the sound is no more audible to him. The examiner then, by operating the lever arm 43 of the fatigue shutter 42, brings it into position between the ear of the patient and the tuning fork, and after holding it in that position for a brief period of time, possibly a second or so, again removes the shutter and the patient may again for a while hear the sound. This operation of actuating the shutter 42 is repeated several times until the patient signals that he does not hear the sound any more, at which time the stop watch is stopped, and the period of audibility, in seconds, is noted. The carriage is 100 then moved by manipulating the handle 38 until each of the forks 18, 19, 20, 21 and 22 are successively brought into position for receiving the impact of the hammer released from the same height,—and in each case the test is conducted 105 and the observations made just as in the case of fork 17.

It can be explained at this point that the reason for operating the fatigue shutter as herein described is to obviate the usual method of repeatedly removing and replacing the fork from and to the ear of the patient to offset the error resulting from nerve fatigue or perception fatigue. As this shutter is a sound insulator, it will, when interposed between the ear of the 115 patient and the sound emitting instrument, either cut off entirely or reduce the sound reaching the patient's ear, thereby resting the ear periodically and permitting it to properly function again when the shutter is removed. It should also be 120 noted that the ear rest 33 is not only adapted for the comfort of the examined person, but also serves the purpose of constantly keeping his ear a given distance from the sound emitting instruments, making for precision and accuracy.

After observations are recorded, they are plotted on the acumetric chart which I have devised and which is shown on Figure 4, the points being connected by a curve, which will be the curve of acuity of the patient tested. To render 130 such a chart of clinical value, the patient's curve should be compared with that of a person of normal hearing, and hence a curve of normal acuity, for the same apparatus, should appear on the same chart. Thus, by referring to Figure 135 4, the curve 44 represents the acumetric line of a normal ear and curve 45 is that of the tested ear. The normal curve was obtained as a result of a test of a person of normal hearing, using the same apparatus employed to test the patient, and is a 140 constant for all times and serves as a satisfactory standard. The acoustic differential or amount of hearing loss for each pitch is thus obtained by inspection from the chart, being measurable on the chart, for each pitch, as the vertical distance 145 or the portion of the ordinate between the two curves.

Although preferable to have each of the tuning forks secured in place with the same degree of force or gripping effect, it is obvious that such 150

and arrangement is not absolutely necessary inasmuch as a reduction in the time of vibration due to any excessively strong grip will not affect the final result, the standard curve being obtained 5 as a result of a test of a normal ear conducted on the same apparatus as was used in the test conducted of the patient's ear. The only advantage in having a support permitting the maximum or equal freedom for vibration of all the 10 forks is that a smoother curve will be obtained on the chart.

The segment or quadrant 46 containing readings 47, 48 and 49 can also be employed if desired, to enable tests to be made by releasing the 15 hammer from different levels. Thus, if a person is exceptionally hard of hearing, the hammer may be released when the pendulum is in line with the topmost scale line 47, where the force of impact will be greatest and the resulting amplitude of vibration largest. If it is dropped from the lowermost scale line 49, the amplitude will be less, and the period of vibration smaller. For each scale line on said segment there should be a record of the period of audibility of a normal 20 ear, so that proper comparisons can be made regardless of what level the weight is released from, thereby facilitating tests of persons with various degrees of deafness.

Although the construction herein described 25 embodies an arrangement where the sound producing media are movable and the hammer or sound actuating means is stationary, a reverse arrangement can be employed, within the scope of this invention, where the sound-actuating element can be movable with respect to a stationary assembly of sound emitting media.

Instead of using the entire assembly shown in Figures 1 and 2 for a wide range of pitches, a test for a single pitch can be conducted by employing the arrangement shown in Figure 5. Here the fork 50 has secured thereto the combination ear rest and fatigue shutter 51 similar to that used on the assembly illustrated in Figures 1 and 2. By holding the ear rest to the ear to be tested, and periodically operating the shutter as hereinbefore described, the period of audibility can be obtained, and by comparing the results so obtained with that of a normal ear, the acoustic differential can be computed for a particular 50 tuning fork.

Other changes and modifications can be made within the scope of the appended claims, without departing from the spirit of this invention.

What I claim is:

55 1. In an apparatus for testing the acuity of hearing, a vibratory sound producing medium, a swingingly mounted drop-weight, means for releasably holding said weight at a predetermined height, said weight when released being adapted to strike said medium to produce a prolonged sound therefrom, and means positioned adjacent to and fixed at a predetermined distance from said medium for accommodating the ear of a listener.

60 2. In an apparatus for testing the acuity of hearing, a vibratory sound producing medium, a swingingly mounted drop-weight, means for releasably holding said weight at a predetermined height, said weight when released being adapted to strike said medium to produce a prolonged sound therefrom, and an ear rest positioned in fixed relation to and adjacent said medium and containing an aperture therein for the passage therethrough to the ear of a listener of the sounds emitted from said medium.

3. In an apparatus for testing the acuity of hearing, a vibratory sound producing medium, a swingingly mounted drop-weight, means for releasably holding said weight at a predetermined height, said weight when released being adapted to strike said medium to produce a prolonged sound therefrom, and sound insulating means removably interposed between said medium and the ear of a listener. 80

4. In an apparatus for testing the acuity of hearing, a vibratory sound producing medium, a swingingly mounted drop-weight, means for releasably holding said weight at a predetermined height, said weight when released being adapted to strike said medium to produce a prolonged sound therefrom, an ear rest positioned in fixed relation to and adjacent said medium and containing an aperture therein for the passage therethrough to the ear of a listener of the sound emitted from said medium, and sound insulating means associated with said ear rest and removably interposed between said medium and the ear of a listener. 85

5. In an apparatus for testing the acuity of hearing, a plurality of sound producing media of predetermined pitches, a single means adapted to coat with each of said media to produce a prolonged sound therefrom, and means to successively bring said latter means and each of said media into operative positions with respect to each other. 90

6. In an apparatus for testing the acuity of hearing, a plurality of vibratory sound producing media of predetermined pitches, a single means adapted to engage with equal force each of said media to produce a prolonged sound therefrom, and means to movably bring said single means and each of said media into operative positions with respect to each other. 105

7. In an apparatus for testing the acuity of hearing, a stationary support, a swingingly mounted drop-weight, means for releasably holding said weight at a predetermined height, a base movable with reference to said support, a plurality of vibratory sound producing instruments mounted on said base, and means to move said base so as to successively bring each of said instruments into position to receive the impact of said weight upon the release thereof. 115

8. In an apparatus for testing the acuity of hearing, a stationary support, a swingingly mounted drop-weight, means for releasably holding said weight at a predetermined height, a base movable with reference to said support, a plurality of vibratory sound producing instruments mounted on said base, means to move said base so as to successively bring each of said instruments into position to receive the impact of said weight upon the release thereof, and a stationary ear rest so positioned as to be adjacent each instrument 120 as it is in position to receive the impact of said weight. 130

9. In an apparatus for testing the acuity of hearing, a stationary support, a swingingly mounted drop-weight, means for releasably holding said weight at a predetermined height, a base movable with reference to said support, a plurality of vibratory sound producing instruments mounted on said base, means to move said base so as to successively bring each of said instruments into position to receive the impact of said weight upon the release thereof, a stationary ear rest so positioned as to be adjacent each instrument as it is in position to receive the impact of said weight, sound insulating means associated with said ear 140 145 150

rest and operatively interposed between the ear of a listener and said instruments, and means for removing said insulating means from its operative position.

5 10. In an apparatus for testing the acuity of hearing, a sound producing medium and a combination ear rest and fatigue shutter associated therewith, said ear rest having an aperture therein adjacent said medium and being adapted to 10 accommodate the ear of a listener, and said shutter being movably connected to said ear rest and adapted for removable placement over said aperture.

11. In an apparatus for testing the acuity of 15 hearing, a sound producing medium and a combination ear rest and fatigue shutter associated therewith, said ear rest being attached to said medium and having an aperture therein adjacent a sound producing portion of said medium, said 20 shutter being pivotally connected to said ear rest and having a portion thereof adapted to cover said aperture and an extending portion adapted for manual manipulation to pivotally actuate said shutter, and means to hold said shutter in its projected position.

25 12. In an apparatus for testing the acuity of hearing, a tuning fork, means for striking said fork to produce a prolonged sound therefrom, and a yieldable and pivotal supporting means

and intermediate yieldable supports for said upright.

15 80 16. In an apparatus for testing the acuity of hearing, a sound producing medium, a swingingly mounted drop-weight adapted to strike said medium, yieldable means for frictionally and normally holding said weight against downward movement, and manipulating means operable against said yieldable means for releasing said weight to permit it to strike said medium and rebound therefrom, said yieldable means being adapted to frictionally hold said weight in its 85 rebounded position after the release of said manipulating means.

16 90 85 95 17. In an apparatus for testing the acuity of hearing, a sound producing medium, a swingingly mounted drop-weight, a scale having markings thereon at different levels, yieldable means for releasably holding said weight at any of said markings, said weight when released being adapted to strike said medium to produce a prolonged sound therefrom.

17. The method of testing and determining the acuity of hearing, consisting of the steps of recording the period of lost audibility for a normal 100 ear of each of a series of sound emitting instruments of predetermined pitches by successively placing said normal ear to each of said instruments, at a fixed distance therefrom, actuating
